UNITED STATES PATENT OFFICE.

ROY J. COOK, OF CHICAGO, ILLINOIS, ASSIGNOR TO GEORGE C. MURRAY, OF CHICAGO, ILLINOIS.

FRICTIONAL DRAFT GEAR.

Application filed December 30, 1918. Serial No. 268,944.

To all whom it may concern:

Be it known that I, Roy J. Cook, a citizen of the United States, residing at Chicago, in the county of Cook and State of Illinois, have invented certain new and useful Improvements in Frictional Draft Gears, of which the following is a specification.

This invention relates to improvements in friction draft gears for railway cars, and the like, and its purpose is to provide an improved draft gear attachment comprising a small number of parts, without sacrifice of efficiency. The principal object of the invention is to provide a friction draft gear having a single spring, in combination with an improved construction and arrangement of friction elements. A further object is to provide a draft gear comprising a supplementary yoke. Another object is to provide improved means for mounting the friction elements within the drawbar yoke. Other objects relate to various features of construction and arrangement which will be pointed out more fully hereinafter.

25 In the drawings—

Figure 1 shows a top plan view of my invention with a portion thereof illustrated in horizontal section on the line 1—1 of Fig. 2;

30 Fig. 2 shows a transverse sectional view, taken on the line 2—2 of Fig. 6;

Fig. 3 shows a perspective view of one of the friction blocks;

35 Fig. 4 shows a perspective view of another friction block;

Fig. 5 shows a perspective view of the rear follower or casing;

40 Fig. 6 shows a side elevation of the invention with the lower part thereof illustrated in vertical section on the line 6—6 of Fig. 2;

Fig. 7 shows a perspective view of the front casing or follower; and

Fig. 8 shows a perspective view of the supplementary or inside yoke.

45 In the drawings the invention is illustrated as being mounted between the usual draft sills 10, of channel form, which have the draft lugs 11 secured thereto by rivets 12. The draft rigging is supported by the carrier bars 13, which are secured to the lower flanges of the draft sills by bolts or rivets 14. The drawbar yoke 15 is of the usual form, having the upper and lower

arms thereof secured by rivets 16 to the butt 17^a of the drawbar 17. The lower wall of 55 the yoke is adapted to engage the depressions 13^a in the carrier bars 13.

Mounted within the forward ends of the yoke 15 is the front casing or follower 20, which is of the form illustrated particularly 60 in Fig. 7. It comprises parallel upper and lower walls 21 and 22, respectively, connected at their forward ends by the integral forward wall 23. The upper and lower walls are united at their rear ends by the inclined 65 converging walls 24, and reinforcing ribs or webs 25 extend forwardly from the inclined walls 24 to the forward wall 23. The inner edges of the inclined walls 24 are shown at 24^a for a purpose hereinafter to be 70 described, and the upper and lower walls are provided with openings 27. This casing 20 is adapted to rest upon the forward carrier bar 13.

The rear follower 30 seats against the rear 75 wall of the yoke 15, and is of the form illustrated particularly in Fig. 5. It comprises upper and lower walls 31 and 32, respectively, which are united by the inclined diverging walls 33. The upper and lower 80 walls and the diverging walls are united at their rear ends by the rear wall 34, and reinforcing webs 35 extend between the rear wall and the inclined walls 33.

The supplementary yoke 38 is mounted 85 within the casing 20, and extends into the rear follower 30. This supplementary yoke is of rectangular form, as shown in Figs. 6 and 8, the same being provided with upper and lower walls 38^a and 38^b, respectively, 90 which are united by the front wall 38^c and the rear wall 38^d. This supplementary yoke serves as a container for the friction blocks 39, which are triangular in cross section, as shown in Figs. 1 and 4, and which fit between the upper and lower walls of the supplementary yoke. These wedge blocks are hollow, and are reinforced by a central web 39^a, as shown in Fig. 4. Two of these wedge blocks are arranged in the manner shown in Fig. 1, and the diverging inclined faces 39^b thereof are adapted to coat with the surfaces 40^a of the outside wedge blocks 40, which are of the form illustrated in Fig. 3. These outside wedge 105 blocks are provided with six faces or walls,

including the surfaces 40^b, which coact with the diverging walls 24 and 33 of the front casing and rear follower, respectively. The wedge blocks 40 are hollow, and are reinforced by transverse webs 40^c, as shown in Fig. 3. They are further provided with notches 40^a to provide clearance for the upper and lower walls of the supplementary yoke 38 when these blocks move inwardly, due to the compression of the draft rigging, it being understood that the friction blocks 40 fit between the upper and lower walls of the front casing and the rear follower, and rest upon the lower walls 22 and 32, which walls also serve to support the supplementary yoke. The central wedge blocks 39 are provided with registering notches 41, and the outside wedge blocks are provided with alining openings 42, which permit a bolt to pass therethrough for holding the draft rigging in assembled relation when it is not in position between the draft sills, with a coil spring 43 extending between the inclined walls 24 of the front casing, as permitted by the notches 24^a, previously described, and seating at one end against the forward block 39. At the other end this spring engages the forward wall 38^c of the supplementary yoke 38. The front wall is provided with a dowel pin or lug 44, and the rear wall of the supplementary yoke is provided with another dowel pin or lug 45, these lugs being adapted to engage the spring 43 and an aperture in the rear wedge block 39, respectively, in order to prevent lateral displacement of the parts of the apparatus.

Upon forward movement of the drawbar, the rear wall of the yoke 15 moves the rear follower 30 in a forward direction, thereby causing the outside blocks 40 to move inwardly on the inclined walls 24 and 33 of the front casing and the rear follower. At the same time the rear wedge block 39 moves rearwardly on the inclined surfaces 40^a of the outside wedge blocks, and the front wedge block 39 moves forwardly on the coacting surfaces of the blocks 40, thereby causing the spring 43 to be compressed by the forward movement of the forward block 39 and the simultaneous rearward movement of the supplementary yoke 38, due to the rearward movement of the rear wedge block 39^b. When the drawbar is moved in a rearward direction, the front casing 20 is moved rearwardly, while the rear follower 30 remains stationary against the rear draft lugs 11, thus causing the outside blocks 40 to move inwardly in the manner previously described, thereby operating the central wedge blocks 39 and compressing the spring 43, as will be readily understood.

Although I have shown and described a single embodiment of the invention for purposes of illustration, it will be understood

that it may be constructed in various different forms without departing from the scope of the appended claims.

I claim:

1. In combination a yoke, a draw bar connected to said yoke, a supplementary yoke mounted within and extending longitudinally of said first named yoke, and movement-resisting mechanism coacting with and supported by said first named yoke and supporting said supplemental yoke independently thereof, said movement-resisting mechanism being retained by said supplemental yoke which extends around a portion thereof.

2. In combination a yoke, a casing and a follower mounted in and supported by said yoke, friction movement-resisting mechanism coacting with and supported by said casing and said follower, and a supplemental yoke surrounding said friction movement-resisting mechanism and supported thereby independently of said first named yoke.

3. The combination in a draft gear of oppositely disposed box-like followers, a yoke surrounding said followers and coacting directly therewith, friction movement-resisting mechanism retained in and actuated by said followers, a yielding resistance member co-operating with said friction mechanism, and a supplementary yoke in which said friction mechanism and said yielding resistance member are retained.

4. The combination in a draft gear of a yoke, a pair of box-like followers mounted in opposite ends of said yoke, friction movement resisting mechanism for controlling the relative movements of said followers, said mechanism comprising a supplementary yoke having upper and lower walls and end walls located within said first-named yoke, and draft lugs adapted to coact with said followers.

5. The combination in a draft gear of a yoke, box-like followers mounted in opposite ends of said yoke, side friction blocks coacting with said followers, intermediate friction blocks coacting with said side friction blocks, and means comprising a supplementary yoke extending around said intermediate friction blocks for controlling the relative movements of said friction blocks and said followers.

6. The combination in a draft gear of a yoke, box-like followers mounted in said yoke and having inclined flanges, friction blocks coacting with said inclined flanges, central friction blocks coacting with said first named friction blocks, a supplemental yoke extending around said central friction blocks, and a spring interposed between one of said central friction blocks and the opposite end of said supplemental yoke.

7. The combination in a draft gear of a yoke, box-like followers mounted in said

yoke and having inclined flanges, friction blocks interposed between said followers and coacting with the inclined flanges thereof, said friction blocks having oppositely inclined surfaces converging inwardly, central friction blocks of triangular cross-section coacting with the inwardly converging surface of said first named friction blocks, a supplemental yoke having upper and lower walls and end walls, said supplemental yoke having one end wall engaging one of said central friction blocks, and a spring interposed between the other central friction block and the other end wall of said supplemental yoke, said friction blocks, said spring and said supplemental yoke being retained within said followers.

8. The combination in a draft gear of box-like followers oppositely disposed, friction movement resisting mechanism actuated by one of said followers, a yielding resistance member cooperating with said friction mechanism, and a supplemental yoke in which said friction mechanism and said yielding resistance member are retained, said friction mechanism and said yielding resistance member being operatively connected to said supplemental yoke and to said followers.

9. The combination in a draft gear of a yoke, a box-like follower mounted in one end of said yoke and a second follower mounted in the other end of said yoke, said first follower having inclined flanges diverging toward said second follower, said second follower having inclined flanges diverging toward said first follower, intermediate friction blocks supported by said first follower and said second follower and having inclined surfaces coacting with the inclined flanges thereof, said intermediate blocks having their inclined surfaces converging inwardly, central friction blocks having inclined surfaces coacting with said inwardly converging surfaces of said intermediate friction blocks, a spring engaging one of said central friction blocks and a supplemental yoke extending around said spring and said central friction blocks.

10. The combination in a draft gear of a yoke, a box-like follower mounted in one end of said yoke, and a second follower mounted in the other end of said yoke, said first follower having inclined flanges diverging toward said second follower, said second follower having inclined flanges diverging toward said first follower, intermediate friction blocks supported by said first follower and said second follower and having inclined surfaces coacting with the inclined flanges thereof, said intermediate blocks having their inclined surfaces converging inwardly, central friction blocks having inclined surfaces coacting with said inwardly converging surfaces of said intermediate friction blocks, a spring located within said first follower and coacting with one of said central friction blocks, and means for connecting said spring with the other central friction block.

11. The combination in a draft gear of a yoke, a box-like follower mounted in one end of said yoke, and a second follower mounted in the other end of said yoke, said first follower having inclined flanges diverging toward said second follower, said second follower having inclined flanges diverging toward said first follower, intermediate friction blocks supported by said first follower and said second follower and having inclined surfaces coacting with the inclined flanges thereof, said intermediate blocks having their inclined surfaces converging inwardly, central friction blocks having inclined surfaces coacting with said inwardly converging surfaces of said intermediate friction blocks, a spring engaging one of said central friction blocks and a supplemental yoke extending around said spring and said central friction blocks.

In testimony whereof, I have subscribed my name.

ROY J. COOK.
